ATTORNEY

UNITED STATES PATENT OFFICE.

DAVID H. FINBERG, OF BROOKLYN, NEW YORK, ASSIGNOR TO THE MILLER RUBBER COMPANY, OF AKRON, OHIO, A CORPORATION OF OHIO.

FLEXIBLE-RUBBER SHOE.

Application filed July 22, 1926. Serial No. 124,120.

This invention relates to footwear for men, children, and women and has particular reference to storm or rain-proof shoes or shoe coverings, the subject matter of this application being an improvement over that shown in my co-pending application filed December 19th, 1925, Serial No. 76,362.

Among the objects of this present improvement is to perfect and simplify the construction, making the rubber shoe of better fitting and neater appearing qualities than as heretofore proposed.

More specifically, the present improvement includes re-enforcing means for the fly or front opening of the shoe to accommodate the fastening devices; to improve the toe tip construction; to improve the heel hole construction and binding, and to improve the lining elements which make for the easy slipping on or off of the rubber shoe over the dress shoe, and yet without disturbing the flexibility of the main parts of the upper, whereby the same rubber shoe may be fitted readily to dress shoes of several different sizes and widths.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had to the accompanying drawings in which like reference characters designate the same parts in the several views, and in which—

Figure 1 is a side perspective showing the shoe in the form as when worn.

Fig. 2 is a front view, partly open and partly broken away.

Fig. 3 is a bottom plan view.

Fig. 4 is a longitudinal sectional detail of a last indicating the heel hole construction.

Fig. 5 is a fragmentary view showing the inside construction of the back of the upper.

Fig. 6 is a plan view of one of the flat re-enforcement strips.

Fig. 7 is a transverse sectional detail on line 7—7 of Fig. 3.

Fig. 8 is a detail plan view of the sock lining.

Fig. 9 is a detail showing how the heel portion is fitted to the heel of the dress shoe.

Referring now more specifically to the

drawings, the upper, as in the previous application above specified, is made of two substantially equal parts 10^a and 10^b united together along a vertical line 11 at the back and also along the sole at 12, the line of connection between the two parts being extended up over the toe and thence up along the instep as indicated by the dotted line 13. At the rear end the line 12 terminates at a point corresponding to the breast or slightly back of the breast of the heel, the heel hole 14 being left open. The upper sections are composed preferably of relatively thin pliable and elastic material such as a good quality of sheet rubber, the same adapting the shoe for application like a glove over an ordinary dress shoe or slipper.

As a lining for the sole portion of the shoe I provide what is termed a sock lining 15 approximating the length and width of the sole, the main portion of which lies substantially flat within the shoe, but extending laterally from the sides of the main portion are two lip members 16 which may be made integral with the main portion 15, but for better fitting they are made as separate elements and having overlapping engagement with the part 15. See Figs. 7 and 8.

Secured within the rear portion of the upper is a lining strip 17 which like the sock lining is made preferably of fabric so as to be substantially non-elastic and which permits the easy slipping of the rubber shoe on or off from the dress shoe. The upper end of the lining 17 is spaced from the top of the upper leaving a clearance 18, and the lower end of the lining is flared laterally at 19 to provide a better re-enforcement for the counter portion of the construction, and it too is spaced from the next adjacent edge 20 or opening 14 as at 20. These clearances 18 and 20 afford ample freedom of adjustment or spreading of the edge portions of the shoe, while the lining itself affords sufficient strength for the purpose of drawing on the overshoe.

In practice these shoes are built over a last. The sock lining and fabric re-enforcement strip are applied first to the sole and back portion of the last and secured there temporarily to maintain them in proper position. The upper sections 10^a and 10^b are then put in place and fitted to the last and to each other preliminary to curing.

21 indicates a half sole applied over the

sole portions of the upper and having its margins indicated at the dotted line of Fig. 3. Over the half sole and the margins of the ball of the shoe is secured an outsole 22, 5 the edges of which extend upward somewhat from the floor line as shown at 23, this element extending from around the toe rearward and around the heel hole at 24. The parts 21 and 22 may be made of any suitable material, but preferably of flexible and elastic rubber stock. For the sake of neatness and attractiveness of appearance the upper and trimming members are preferably of different colors, but as to this I do not 10 propose to be limited.

As indicated in Fig. 4 the last L is formed around the heel portion l with a groove or channel into which the stock of the upper is forced, thereby distorting the stock somewhat 15 into a reverse form or position from that assumed when the shoe is worn. Any suitable re-enforcement for strengthening the heel hole in the finished article may be employed, but I show for this purpose a 20 special binding strip 25 of rubber facing the edge portion of the upper as it lies within the groove in the last, and I also show a rubber cord or bead 26 forced finally into the groove, bearing at one side against the 25 rubber stock aforesaid, and at another side against the portion l of the last. This construction makes a smooth neat finish for the edge 14 of the heel which, moreover, is of a flexible nature and calculated to fit snugly 30 around the top portion of the dress shoe heel H in such a manner that the tighter up the shoe is drawn over the heel, the more snugly it fits around the heel, thereby reducing the 35 possibility of rain, snow, or other moisture 40 from reaching the dress shoe. See Fig. 9.

The top of the shoe is re-enforced by an ornamental cuff 27 of flexible rubber, and extending downward from the top to the rear portion of the heel opening is a re-enforcement strip 28 which covers the joint at 45 18 and presents a neat finish for the shoe.

Any suitable fastening means may be provided for the fly or front of the shoe. In the preferred form and as now practised by 50 me, I provide a pair of fabric strips 29 which, though they are flexible, are practically non-elastic. One of these strips is secured along the inside surface of the fly, while the other is secured along the inner 55 surface of an outside tongue or re-enforcement strip 30 of rubber. This facing member 30 overlaps the joint 13 along the front of the shoe all the way down to and under the toe, and is vulcanized to the side of the 60 fly opposite the portion that carries the inside strip 29. Fasteners such as head and socket snap buttons 31 are secured to and through the re-enforcement strips 29 and rubber portions to which they are secured 65 and operate in the usual way. Because of

the curvature of the instep of the shoe the strips 29 are preferably formed arcuate and the lower end of each is given a sharp turn at 29^a where it crosses the seam. The lower end of the tongue 30 may constitute the toe 70 piece, or the toe piece 30^a may be made separate if desired from the tongue. As shown I prefer that the tongue be extended as an integral member down and around the toe where it is overlapped by the toe portion of 75 the outsole 22. The tongue or facing strip 30 preferably overlaps the ends of the cuff member 27 as they come around and meet at the center line of the shoe upper. By extending the cuff in this manner the elastic 80 top portion of the shoe is suitably re-enforced, preventing any possibility of tearing near where it is re-enforced by the non-elastic fabric.

I claim:

1. The herein described flexible rubber shoe whose upper is flexible and elastic and form-fitting, parts of the upper being extended downward forming a part of the sole, the upper being split from the top downward toward the toe, the edges bounding the split lying in abutting relation to each other, a re-enforcement facing tongue of flexible elastic material secured along one edge on the outside of the upper at one side 90 of the split and extending thence across the edge abutting against the same, a flexible re-enforcing strip secured to the inner face of the free portion of said tongue and fastening means co-operating with the free edge 95 of the tongue and the part overlapped thereby.

2. A flexible rubber shoe built of form fitting stock, the upper being provided with a slitted opening, fastening means cooperating with the opening, and lining means including a non-elastic flexible strip of material secured along the inner surface of the back of the upper, and a sock lining conforming to the sole portion of the shoe and secured thereto and having crescent shaped lips on opposite sides of the ball portion thereof.

3. The herein described rubber shoe having an open fly front, the edges of the upper at the fly abutting against each other, a re-enforcement strip of non-elastic material secured along one edge of the fly and having its lower end extending laterally across the line of connection between the two parts of the upper, a one piece facing tongue carried by the other portion of the upper and extending thence laterally across the portion having the non-elastic re-enforcement.

4. A shoe as set forth in claim 3 in which a second non-elastic re-enforcement strip is secured along the inner face of that part of the one piece facing tongue which overlaps the first mentioned re-enforcement strip, fastening means being operative in conjunc- 125 130

tion with said two non-elastic re-enforcement strips.

5. The herein described shoe composed chiefly of flexible elastic rubber having an open front constituting a fly, the edges of the fly being faced with non-elastic re-enforcement means, a finishing cuff extending circumferentially of the top of the shoe and having its ends overlapping the upper ends 10 of the re-enforcement means aforesaid, and an outside facing strip extending vertically over the fly opening and overlapping the ends of the cuff.

6. The herein described overshoe whose upper is flexible and elastic and form fitting, said upper comprising upper portions seamed together along the median line of the toe and being split downward from the top to the instep where said split merges in the 20 seam, a reenforcing facing tongue of flexible material secured along one edge on the outside of the upper at one side of the slit and extending across the slit to overlie the other edge, said facing tongue being extended downward over the toe and being secured thereto in overlying relation to said seam to reenforce the same.

7. The herein described flexible rubber shoe having an upper which is flexible and elastic and form fitting, said upper being split from the top downward towards the toe, the edges defining the split lying when closed in abutting relation, a reenforcing tongue of flexible elastic material secured 35 along one edge of one side of the upper at one side of the split and extending thence

across the split, a flexible non-elastic reenforcing strip secured to the inner face of the projecting portion of the tongue and adapted to overlie the edge portion of the upper on the opposite side of said split, a similar non-elastic reenforcing strip secured to the face of said edge portion, and cooperating fastening means carried by said reenforced tongue and the underlying reenforced edge 45 portion.

8. A shoe having an upper composed of flexible elastic material, parts of the upper being extended to provide sole overlapping portions, said upper having a split in front 50 extending downward into proximity to the toe with the edges of the split adapted to lie in abutting relation when the front is closed, an insole overlying said sole overlapping portions, a one piece facing tongue 55 of flexible elastic material secured to one edge of the upper at one side of said divided front and extending laterally across the line of division, said facing tongue being extended over the toe and under the sole overlapping portions at the front, an outsole having an upturned edge overlapping the lower side portions of the upper and the lower end of the facing tongue at the toe, flexible inelastic reenforcing strips carried by the free 60 portion of the facing tongue and the edge of the upper which said tongue overlies, and cooperating fastening means carried by said reenforced upper edge and the reinforced 65 overlying portion of the facing tongue. 70

In testimony whereof I affix my signature.

DAVID H. FINBERG.
